(57) CLAIM

I claim the ornamental design for a golf club towel and cover, as shown and described.

DESCRIPTION

FIG. 1 is a top elevation view thereof;

FIG. 2 is a bottom elevation view thereof;

FIG. 3 is a left side elevation view thereof, the right side view being a mirror image of that shown; and,

FIG. 4 is a perspective view of a golf club towel and cover, shown in an alternate position.
